UNITED STATES PATENT OFFICE.

GUST GANALLIS, OF DETROIT, MICHIGAN.

DESIGN FOR A BARBER'S STAND.

Application filed April 13, 1923. Serial No. 5,812. Term of patent 14 years.

To all whom it may concern:

Be it known that I, GUST GANALLIS, a citizen of the United States, residing at Detroit, in the county of Wayne and State of Michigan, have invented a new, original, and ornamental Design for Barbers' Stands, of which the following is a specification, reference being had to the accompanying drawing, forming part thereof.

The figure is a perspective view of a barber's stand, showing my new design.

I claim:

The ornamental design for a barber's stand, as shown.

GUST GANALLIS.
